ADJUSTABLE PRINTING MECHANISM

William J. Pearson, Los Angeles, Calif.

Application October 23, 1931, Serial No. 570,625

25 Claims. (Cl. 101—93)

This invention relates to adjustable printing mechanism designed to be used in conjunction with a parcel post machine, such as is disclosed in my co-pending application Serial Number 5 367,106, filed May 29, 1929, entitled Parcel post weighing and stamp printing machine, which is designed to weigh parcel post packages and to print parcel post stamps of the prepaid metered type.

10 The Parcel post weighing and stamp printing machine disclosed in said application is designed for printing purposes, more particularly the printing of metered parcel post stamps, wherein it may be required to print a stamp bearing the 15 name of the place of original mailing, the date, the zone number to which the package is addressed, the weight of the package, the monetary value of the stamp derived from the weight and the zone, a serial number, and such other words, 20 phrases, figures, decorations, and designations as it may be desired to print. This mechanism is used in conjunction with a scale, meters, and a paper supply, and may be motor driven and used for any printing purpose. This mechanism 25 is more particularly designed for the purpose of printing stamps within the postal limits as in use at the present time, namely, from 7¢ to \$6.01 inclusive, the machine described having a capacity of \$9.99, but may be constructed for any 30 capacity desired.

This mechanism is particularly adapted for the printing of parcel post stamps upon a paper strip which is delivered from the machine, cut to the proper stamp length, and, being gummed 35 on the reverse side, may be moistened at the delivery point of the machine and, in this condition, attached to the package to be mailed.

This mechanism is also designed to be used 40 in conjunction with a metering or registering device which continuously registers within a set of numeral wheels constituting a meter the monetary values of the stamps printed; and also with a control meter which may be set for a predetermined monetary value and which, upon exhaustion of the set amount, will function to lock 45 the entire machine against operation until again so set, and may be so disposed as to actuate any other mechanism that may be desired.

This mechanism also provides a novel method 50 of setting up within the machine the mechanical equivalents of numbers put into the machine by an operator by actuation of the keys of a keyboard. This mechanism provides a novel method of setting up a series of type within the machine 55 through the use by an operator of a single bank

of ten keys which, when the required numbers have been set up or the required number of keys operated on the keyboard by means of a control key and the connected motor drive, performs the printing operation, whereupon the entire machine is cleared and re-set preparatory to the next setting and printing operation. In the form of the machine disclosed, there are six numbers to be printed, hence six figures must be set up in the machine and therefore six keys 10 on the keyboard must be punched before the progressive release lock will be fully operated to unlock and allow the printing mechanism to function. Thus, it is impossible to print a stamp until the required number of keys have been 15 punched on the keyboard, no more and no less, thus reducing to a minimum the possibility of printing incorrect or mutilated stamps and the consequent registering of incorrect amounts with- 20 in the recited meters.

An object of my invention is to provide a printing mechanism comprising the peculiar features required by the operation of a machine for the purposes as set forth and to produce the said results, wherein multiple type may be set up by a 25 single keyboard successively for printing purposes, which type may be returned to the original position at the will of the operator and which will be automatically returned to the original position at the completion of a printing operation. 30

An object of my invention is to provide a printing mechanism comprising a series of printing wheels actuated by a keyboard mechanism to be rotated to a position corresponding to the numbers put into the keyboard, successively and in 35 rotation, and presenting the certain type faces in printing relation to a platen.

An object of my invention is to provide a printing mechanism comprising a locking element adapted to engage the recited printing wheels 40 while still in geared relation to the setting means, retaining them in the position as locked during a printing operation and returning them to the said geared relation in the original position assumed before the locking operation occurred. 45

An object of my invention is to provide a printing mechanism comprising a platen against which the type operate to print which includes a duplicating mechanism composed of an inked ribbon and the spools for winding the ribbon, the winding mechanism and reversing mechanism for the ribbon, and runways or guides for the paper strips to pass through under the printer, thus placing the ink ribbon between the two paper strips and allowing the type to print a duplicate stamp by 50 55

means of the force of the blow delivered against the platen.

An object of my invention is to provide a printing mechanism comprising an inking device for inking the type faces of the numeral wheels, wherein there is a reservoir for holding a supply of ink and means to feed the ink to the surface of a pad, and a roller operating in tracks for the purpose of carrying the ink from the pad to the type faces and properly and evenly inking the said type faces; and also to provide means for inking the said type faces in the minimum of time prior to a printing operation of the numeral printer, wherein the said roller is required to travel from an original position at one side of the pad across the face of the pad, to and across the face of the type, and then to return to the original position.

An object of my invention is to provide a printing mechanism comprising an automatically operated serial numbering device having numeral wheels similar to the just recited numeral wheels and adapted to align and print with the other parts of the printer and to be inked by the same recited inking device, and operated to increase the reading by one number each time that a printing operation occurs, and to be actuated by the same means as the printer to print both an original and a duplicate impression.

An object of my invention is to provide a printing mechanism comprising a dater device with removable and replaceable type with type faces bearing letters and numerals for composing the date. The type are enclosed within a dater body which is removable and replaceable in the machine and aligns with the type faces on the recited numeral wheels, is inked and operated by the same means and at the same time as the recited numeral printer, and is provided with a positioning device including an electric switch in the motor circuit, which is opened when the dater block is removed, and which will not be closed unless the dater block is again correctly positioned in the printer. This provides means preventing operation of the machine when the dater is absent or incorrectly positioned, and precludes mutilating a stamp from this cause.

An object of my invention is to provide a printing mechanism including a driving mechanism wherein the motive power is continuously supplied but intermittently connected to the printer parts for actuation only at such points in the cycle of operation as relate with other operative parts of the machine. This I have provided in a novel clutch mechanism which intermittently engages and disengages the drive elements with the driven elements.

An object of my invention is to provide a printing mechanism including, with the recited numeral printer, the combination of a second printer, this printer being a self-inking rotary printer bearing the indicia plate for the printing of a stamp, and using ink of a different color from the ink used in the numeral printer, giving greater visibility in reading by reason of the contrast. This rotary printer is operated, together with the conveyer rolls, by the recited intermittent clutch; and it further drives, with the same intermittent movement, a take-up spindle for the duplicate type whereon it is rolled and which may be removed at the will of the operator.

Various other objects and advantages will be more fully apparent from the following description of the accompanying drawings which form a

part of this disclosure and which illustrate a preferred form of embodiment of the invention.

Of the drawings:

Fig. 1 is a plan view of that portion of a parcel post machine comprising the right-hand front corner of the base plate, the casing being broken away so as to disclose the interior mechanism which includes the keyboard, the re-set meter, the power clutch, the progressive release locking mechanism, the selector, and the meter set-up mechanism. 5

Fig. 2 is a plan view of that portion of a parcel post machine residing adjacent and to the left of that portion shown in Fig. 1, the casing being broken away so as to disclose the interior mechanism which comprises the rotary printer and its attendant clutch and geared connections, the numeral printer, the moistener, the recording meter and the meter-controlled switch in a power circuit. 10

Fig. 3 is a vertical sectional view approximately on line 3—3 on Figs. 1 and 2 and showing the numeral printer, the selector, and a sectional view of the key bars and their attendant connections. 15

Fig. 4 is a plan view of the rear portion of the machine, comprising that portion of the machine not shown in Figs. 1 and 2, the casing being broken away to show the interior mechanism, including the electric motor for a motor-driven machine, a transformer for providing a low voltage current for certain portions of the control and signal mechanism, the paper roll feed and the solenoid operated switches which are a part of the control mechanism. 20

Fig. 5 is an enlarged elevational view, partly in section from the left of the rotary and numeral printers taken approximately on the line 5—5 on Fig. 2, parts being removed to show parts otherwise hidden. 25

Fig. 6 is a front elevational view of the numeral printer taken approximately on the line 6—6 of Fig. 2 with certain parts broken away to show those otherwise hidden. 30

Fig. 7 is a view of the numeral printer drive cam, taken opposite to the view shown in Fig. 6. 45

Fig. 8 is an enlarged sectional view, similar to the left-hand portion of Fig. 3, and showing the numeral printer with the front plate removed, showing certain parts in section and disclosing a diagrammatic view of the various cams and levers 50 contained therein and the adjoining selector unit.

Fig. 9 is a sectional view similar to Fig. 8 of a numeral printer, taken approximately on the line 9—9 of Fig. 5 and disclosing the cams and levers operating the automatic numbering machine and 55 inking device, with the printer in non-printing position.

Fig. 10 is a fragmentary sectional view taken at approximately the same position as Fig. 9 and showing the relative positions of the printing elements in printing position. 60

Fig. 11 is a vertical sectional view of the numeral printer taken approximately on the line 11—11 of Fig. 5 and disclosing the printing hammer and one of the rack and pinion elements 65 which actuate the numeral printing wheels, as well as the selector that operates the racks.

Fig. 12 is a vertical sectional view of the numeral printer, taken approximately on the line 12—12 of Fig. 5 and disclosing in section the dater device which is included as a part of the numeral printer and here shown in non-printing position. 70

Fig. 13 is a vertical sectional view of the printer only, as shown in Fig. 12, disclosing the dater device in section and in printing position. 75

Fig. 14 is an enlarged vertical sectional view, showing the rear ends of the key bars and one complete connection from one of the key bars to one of the push bars which actuate the selector.

5 Fig. 15 is a vertical sectional view of the numeral printer, taken approximately on a line with arrows 15 in Fig. 5 and showing the opposite view of the various levers and connections heretofore disclosed.

10 Fig. 16 is a vertical sectional view of the numeral printer taken approximately on the line 16-16 of Fig. 2.

Fig. 17 is a fragmental sectional view of the numeral printer in printing position.

15 Figs. 1, 2, and 4 provide together a plan view of the entire machine; the keyboard A is located at the right-hand corner at the front in a convenient location for operation by an operator; extending backward from this keyboard are key bars B which by their several connections operate the selector unit C which, in turn, operates the numeral printer D, (best shown in Fig. 2), and, by various connections, the meter set-up unit E in which is set up a mechanical equivalent 20 of the numbers punched in on the key board A by an operator; upon a printing operation being instituted, these mechanical equivalents are transmitted into the two meters of which the re-set meter F is disclosed immediately behind 25 the keyboard A in Fig. 1 and the total meter G is disclosed adjacent the front of the machine in Fig. 2.

30 As these elements of the machine are actuated simultaneously during a set-up and a printing operation, their complete construction and operation will be described, as well as that of the rotary printer H (Fig. 2), which functions to print the indicia upon the paper tape in the form of a stamp preparatory to the action of the numeral printer to print the numerals thereon, completing the printing operation of a stamp.

35 There are several units which control or govern the operations of all of these units prior to and during printing operations. Among those 40 that most directly affect the printing mechanism are the meter-controlled lock J (Fig. 1), and the connected meter-controlled switch K (Fig. 2), which opens the motor circuit upon the exhaustion of a pre-set amount of postage in the 45 re-set meter which is adapted to be set by the postmaster for an amount of postage purchased by the consumer; lock J and switch K are returned to normal position upon the operation of re-setting the re-set member by the postmaster.

50 A control device is provided to govern the operation of the printer within the limits of the present keyboard construction, namely, that there must be six keys punched in on the keyboard before a printing operation can be performed; this device consists of the progressive 55 release lock M (Fig. 1), which operates to release the power clutch L upon the proper operation of the keyboard.

55 In addition, there are (Fig. 4) the paper supply units comprising the roll carrier N and the solenoid-operated switch O, the transformer P, a main switch Q (key-operated from the outside of the machine), an electric motor R supplying motive power for the operation of the machine 60 and its gearing and speed reducing units S.

65 In the operation of this machine, the paper tape is carried from the rolls N (Fig. 4) through the rotary printer H and the numeral printer D, where a duplicate copy is made on one of the 70 paper tapes through the original paper tape

which comprises the stamp, and thence to a moistener T, where, when the stamp has been forwarded its length into the moistener, it is severed from the balance of the tape and, at the will of the operator, may be discharged by manual operation, during which operation the gummed surface of the stamp is moistened, while the duplicate stamp is rolled up within the machine for future use.

Owing to the peculiar operation requirements 10 of this particular character of work, there is a requirement for a printer of a flexible character wherein the series of numbers may be set up on type wheels and wherein, should an error occur during the set-up operation, the operator may 15 manually return the numeral wheels to their original position and make a new and correct set-up. This work must be done without affecting the previous registering in the meters of numerals printed; to that end I have provided the 20 recited meter set-up mechanism E wherein there is made a set-up composed of a mechanical equivalent of the numbers punched in on the keyboard A by an operator, and, whereby, when the printing operation occurs, these mechanical 25 equivalents are put into the meters, but, should an error occur, it is necessary to clear the machine of whatever set-up may have been put into it prior to a printing operation, that these mechanical equivalent numbers not be 30 registered within the meters at the time that a set-up is being made. By my meter set-up mechanism the set-up may be cleared without interfering with the meter action. This mechanism is the subject of a co-pending application filed 35 October 23, 1931, Serial Number 570,620.

The progressive release lock M governs the printing operations of the machine for the purpose of more completely eliminating the possibility of error in numbers set-up within the 40 printer by means of the keyboard, for example, if less than six or more than six keys are punched inadvertently, the printing mechanism cannot be operated because the power clutch L has not been released by the progressive release lock M; 45 the operator must then clear the machine and properly set up the number by effecting the required number of key-actuations on the keyboard; with this operation properly completed, the power clutch L is released and may be 50 engaged by means controlled from the keyboard. At the completion of the printing operation, the progressive release lock M is automatically set in locking position against the power clutch L, and so remains until the next complete keyboard 55 operation.

I will now describe in detail the numeral printer D to which this application primarily pertains.

Fig. 6, which illustrates the numeral printer as a unit, shows the base of the machine 20 upon 60 which is mounted the frame 21 of the numeral printer and a similar oppositely-disposed frame 22 (Figs. 8 and 12) to which most of the elements comprising the printer are secured.

Associated with a series of numeral wheels 23, 65 24, 25, 26, 27, and 28 (Fig. 5) which comprise the so-called numeral printer, is an automatic numbering machine 29 which comprises three numeral wheels 30 similar to the numeral wheels of the numeral printer and aligned to print with 70 them. The numeral printer also includes a dating device 31 which is the subject of a co-pending application Serial Number 570,628, filed October 23, 1931. This dating device comprises a dater block 32 which is adapted to receive the type 75

33, and has a handle 34 for removal from the carriage 35 in which it resides when in operative position in the numeral printer; this device is also provided with a positioning pin 36, and a 5 manually movable switch control arm 37 which operates the positioning pin 36 and which, when moved in either lateral direction, disconnects the switch contact points 38 in the electric circuit supplying the electric motor R (Figs. 5 and 16).

10 The positioning pin 36 may be manually removed from contact with the dater block 32 for the purpose of removing the block for re-setting the type; and, when the switch control arm 37 is moved out for this purpose, the switch contacts 15 38 are disconnected, and, after the dater block 32 is removed and the arm 37 released, it moves laterally in the opposite direction a sufficient amount to disconnect the switch points 38, and thus the motor circuit is broken while the dater 20 block is out. Should the dater block be returned to the printer in an incorrect position wherein the positioning pin 36 does not properly seat itself in the dater block 32, the switch contacts 38 will remain open until the dater block 32 is properly 25 positioned and the pin 36 properly seated. This mechanism prevents operation of the numeral printer when the dater is removed or is in an incorrect position.

30 The dater carriage 35 (Fig. 5) constitutes a bearing for one end of the shaft 39, upon which are rotatably mounted the numeral printer wheels and the wheels of the automatic numbering machine 29. The other end of the shaft 39 is mounted in a sliding plate 40, (Fig. 15). The 35 two plates 40 at either end of the numeral printer support the dater, numeral wheels, and automatic numbering machine, and are attached to an upper plate 41. The sliding plates 40 ride vertically between rails 42 secured to the inside 40 of the frame parts 21 and 22 (Fig. 10). Secured to the inside of the slide plates 40 are rails 43 between which slide the end guide plates 44 attached to the hammer 45. The frames 21 and 22 are tied together at the top by a cross plate 46 and 45 across the front by tie plate 47.

It being required, in this form of a parcel post machine, that the numeral printer be operated with a hammer-like blow for the purpose of printing the duplicate stamp through an inked 50 ribbon, I have provided for this purpose a means comprising a driven shaft 48 to which are secured arms 49 which oscillate to operate the hammer 45 with a reciprocating movement; the connection between the arms and hammer is of a 55 slideable type in the form of a pin 50 secured to the hammer 45 and riding in an elongated opening 51 in one end of the arms 49, thus permitting arcuate movement of the arms.

It being also required, in a machine of this 60 character, that it be impossible to obtain a stamp surreptitiously, I have provided a means to that end. The numeral wheels 23, 24, 25, 26, 27, and 28 are set up by means of the keyboard A and the intervening mechanism culminating in a 65 series of rack bars 52, (one of which is illustrated in Fig. 11), each rack bar has a rack section 53 adapted to engage a pinion wheel 54 secured to one of the numeral wheels. The particular rack bars 52 which operate numeral wheels 26, 27, and 70 28, for printing the monetary value of the stamp are provided with extensions 55 (Figs. 8, 9, and 11), which extend to and operate rack bars 56, 57, and 58 which, through various connections, 75 actuate the meter set-up unit E; by this means any numeral set-up on the monetary numeral

wheels in the printer has a corresponding set-up in the meter set-up mechanism E.

To provide for positively printing the exact 5 numeral set-up made by the arrangement of the numeral wheels, I have provided, on the lower face of the hammer 45, a series of locking devices 45' each of which is adapted to engage the projecting type upon the numeral wheel which is presented toward the hammer. The two positions of the hammer relative to one of the numeral wheels are best shown in Figs. 9 and 10; Fig. 9 discloses the relative position of the parts when in non-printing position and Fig. 10 shows these parts in their engaged and printing position.

The printing operations of the hammer consist in an initial downward movement sufficient to engage the type member presented toward it, for the balance of its downward movement the hammer carries with it the entire numeral wheel 20 assembly to a point where the type presented to the printing surface contacts the paper tape and completes the printing operation. The carriage, comprising the plates 40 and 41, permits the hammer to move vertically. The springs 59 in 25 chambers 60 within the hammer 45 are tensioned upwardly against the plate 41, and after the printing operation raise the entire carriage containing the numeral printer to its original position (Fig. 9). The downward movement of 30 the numeral printer disengages the racks 52 from the pinions 54, the upward return movement again engages these members in identically the same position that they occupied before the printing operation occurred and before the locks 35 45' have been disengaged therefrom.

When the operator of a machine has set up the desired combinations of figures, which, in this instance, we will assume to be correct, and he desires to print a stamp, he may depress the 40 control key 61 on the keyboard A to engage the power clutch L and thus transmit power from the electric motor R through the several connections to the main drive shaft 62; this shaft is gear-related to a secondary gear shaft 63 which, 45 in turn, is gear-related to the numeral printer D by means of a drive gear wheel 64 which meshes with a second gear wheel 65 keyed to the driven shaft 66. The driven shaft 66 is supported by bearings mounted in the frames 21 50 and 22 and has keyed to it on one end a cam wheel 67 which is provided on one side with a cam 68 having a cam groove 69 in which rides cam roller 70 mounted in one end of a rocking arm 71 keyed to the shaft 48. The rocking arm 55 71 is provided at its other end with a tension spring 72 secured to the frame 21. The shaft 48 has keyed to it the arms 49 which operate the hammer 45.

To operate the numeral printer by a hammer-like blow the hammer 45 is associated with the cam 68 and spring tension means. The hammer blow is effected by releasing the numeral printer so that the tension of the spring 72 instantly operates the rocking arm 71 and through 65 it the shaft 48 and the connected hammer 45. The means for releasing these elements for the hammer blow comprises a pin 73 fastened to one side of the rocking lever 71 which is contacted by a latch portion 74 of the trip lever 75; lever 75 is rockably mounted on shaft 76 secured to frame 21 and tensioned into engaged position by means of a spring 77 secured at one end to the lever 75 and at its other end to frame 21.

For the purpose of tripping the lever 75 out 75

of engagement with the pin 73, a trip pin 78 is mounted at a predetermined point upon the periphery of the cam wheel 67; upon the revolution of the cam wheel the pin 78' contacts the lever 75 and rocks it the required amount to disengage the latch 74 from the pin 73, thus allowing the spring-tensioned rocking lever 71 to rock the shaft 48 and perform a printing operation (see Figs. 6 and 7). Owing to the fact that the opposite end of the rocking lever 71 is provided with the cam roller 70 which rides within the cam groove 69 at all times, I have designed the shape of the walls of the cam groove 69 to permit a certain amount of free movement in one direction upon the cam 68 reaching a predetermined point in its cycle of operation, that is, at the point where the trip pin 78 is arranged to contact the lever 75, thereby providing free movement of the lever 71 in its relation to the cam groove 69 when it is operated by means of the spring 72.

The serial numbering device 29 incorporated into the numeral printer automatically steps up one number at each operation of the printer 40 and numbers the stamps successively as they are printed. This device (see Fig. 9) is operated by shaft 66 through the cam 79 keyed to the shaft, cam 79 contacting a cam roller 80 mounted in one end of a bell crank lever 81 fulcrumed on shaft 76; bell crank 81 is connected at its opposite end with a link 82 which operates a bell crank lever 83 fulcrumed on the printer shaft 36; a pawl 84 mounted on lever 83 is tensioned by spring 85 to contact the teeth of a ratchet wheel 86 secured to one of the numeral wheels 39 of the automatic numbering device 29.

The ratchet wheel 86 is restrained against reversing by means of the ratchet dog device 87. The bell crank lever 81 and its cam roller 80 are tensioned toward the cam 79 by spring 88; thus, upon each cycle of operation of the machine, the cam 79 rotates one complete revolution, thus rocking the bell crank 81 and thereby actuating the serial numbering device 29 to advance one unit.

In the cycle of operation of this machine, the sequence of movements requires that the first operation to take place in printing a stamp must be the printing operation of the numeral printer; to provide for this operation in a minimum of elapsed time an inking device is designed to move with great rapidity and yet absolute efficiency to distribute ink to the type faces of the numeral printer and to be removed therefrom prior to the printing operation without interfering with the vertical movement of the hammer and the numeral printer.

The operation of the inking mechanism (Figs. 8 and 11), originates at shaft 66 to which is keyed a cam 89 contacting a cam roller 90 mounted on a swinging lever 91; this lever is fulcrumed at one end on pin 92 mounted in the bifurcated head of a supporting standard 93. The amount of movement originating by the travel of the cam roller 90 in and out of the dwell 94 in cam 89 is multiplied by a series of levers mounted on a rock shaft 95, journaled in plates 21 and 22. One end of the swinging lever 91 is connected to a link 96 which is connected to and operates a lever 97 keyed to the shaft 95; also keyed to shaft 95 are multiplying levers 98, each of which is pivotally connected to a slide member 99 reciprocal in tracks 100; these slide members support the ink roller 101, operate it across the face of an ink pad 102, and carry it into contact with the type faces 75 of the numeral printer and return it to its orig-

inal position adjacent one edge of the ink pad 102.

The ink pad 102 comprises a reservoir 103 and a fabric surface 104 which the ink roller 101 contacts in its travel; the reservoir 103 is provided with a feed spout 103a by which it may be supplied with ink. To effect the movement of the inking device by the travel of the cam roller 90 into and out of the dwell 94, the parts are placed under a strong spring tension provided by two springs 98a secured at one end to the levers 98 10 and at the other end to the frames 21 and 22, respectively.

The numeral wheels of the numeral printer are set up by means of the rack bars 52; as shown in Fig. 11, each of these rack bars is provided with ratchet teeth 105 upon which operates a pawl 106. These ratchet teeth 105 are spaced apart a distance sufficient to allow for the rotation of the numeral printing wheels from one type face to the next succeeding type face by the movement of rack bar 52 a distance equivalent to the space between adjacent ratchet teeth 105. Upon a movement of the rack bar 52 following a set-up movement in the keyboard A, the pawl 106 rests against one of the teeth in the ratchet 105 corresponding to the number of the key depressed in keyboard A. This contact is retained throughout the printing operation, thus maintaining the rack bars 52 in the proper set-up position. The pawls 106 are released from the ratchet teeth 105 upon a clearing operation of the machine hereinafter to be described. The rack bars 52 are tensioned against the set-up portion and against the pawls 106 by means of spring 107.

To provide for a positive return of the rack bars 52 and the associated parts which actuate the meter set-up mechanism E, I do not rely solely upon spring action, but have provided a power driven unit which will mechanically return these members to their original position upon a completion of a printing operation. This return mechanism (best illustrated in Figs. 8 and 15) comprises a cam 108 on shaft 66 engaged by cam roller 109 mounted on one side of rocking lever 110; lever 110 is fulcrumed on pin 111 45 mounted in standard 112.

The operation of returning the rack bars 52 requiring considerable multiplication of the movement originating at the cam 108, I have provided a multiplying lever 113 which is rockably mounted on shaft 76 and connected at its shorter end by means of link 114 with the rocking lever 110, and also provided at its longer end with a cross rod 115 which is mounted at its other end in a rocking lever similar to the lever 113 fulcrumed on shaft 76, but not shown. At the completion of a printing operation, the cam 108 has revolved to a point where the cam roller 109 will ride upon the cam face 116, thereby moving the rod 115 into the position shown by broken lines in Fig. 15 where it has picked up the rack bars 52 in whatever position they may have been and returned them to their original position.

As my parcel post machine is designed to provide a duplicate stamp at the time the printing operation takes place, I have provided means for printing the duplicate simultaneously with the printing of the original stamp; this means comprises a ribbon feed unit U. This unit is composed of two supporting frames 117, (Fig. 5), located at either end of the unit and support the platen 118, which in turn supports the paper guide 119.

In Fig. 10 the ink ribbon 120 is shown as wound

upon the spindles 121 and 122 and passing through the guide plate 119 which separates the paper strips one from the other, so that the ribbon 120 may pass between them; ribbon 120 is 5 guarded against friction and wear by means of rollers 123.

The platen 118 is provided with a center portion 118^a of slightly resilient material for receiving the impact of the blow delivered by the 10 hammer 45.

For the purpose of feeding and reversing the ribbon 120, I have provided a feeding and reversing device 124 (Fig. 2) and which is driven by a rocking lever 125 fulcrumed on the post 126 and 15 which has a cam roller 127 contacting the cam 128 driven by an element of the rotary printer H.

The guide 119 has an open receiving end 129 (Fig. 5) adjacent the rotary printer H from which the paper tapes are received; the paper tapes are 20 divided passing through the guide 119; the ribbon ink 120 is fed through guide 119 between and in a transverse direction to the travel of the paper tapes. The guide 119 ends abruptly at the front end of the numeral printer adjacent a cutting device V which comprises a stationary blade 130 and a pivotally mounted blade 131 having a lift 132 for manual operation when threading up the machine with paper tapes. For the purpose of providing a proper lateral contact between the 25 knife blades 130 and 131, a spring 133 bears against the knife arm 134, and is mounted by means of adjusting screw 135 on the frame 21 (Fig. 6).

For operating the knife there is provided cam 35 136 keyed to the shaft 66; cam 136 contacts a cam roller 137 on one end of the knife arm 134; the knife arm 134 is rockably mounted on shaft 76 and is strongly tensioned by means of spring 138 which is secured at its one end, to arm 134 and 40 at its other end to frame 21.

The operation of the knife unit occurs at the completion of a printing operation cycle of the machine at which point the cam 136 will have 45 rotated to a point where the dwell 139 is opposite the cam roller 137 which, under tension of spring 138, will drop into the dwell, thus allowing the knife blades to be closed by spring tension and sever the paper tapes.

The numeral printer D (Figs. 1, 2 and 3) is 50 closely connected in operation with several of the other elements of the machine, and is inoperative until the six numeral wheels have been properly set up by means of the keyboard A and the intervening mechanism.

55 The keyboard A comprises a single bank of ten keys for the setting up operation, an error key 231 for clearing the machine at the will of the operator, and a control key 61 for operating the power clutch to institute a printing operation. This keyboard is provided with a series of power driven clutches the keys being merely releasing levers for the clutches, the power applied through the clutches being transmitted to the selector unit C, which constitutes the contacting element for the numeral printer D. This keyboard and the connected clutches are the subject of a co-pending application filed October 23, 1931, Serial Number 570,622. The series of levers and bars intermediate the clutches and the selector unit C are of conventional form and need little 65 description.

70 The movement originating in the keyboard is transmitted at right angles from the key bars 140 by means of connecting links 141, (Fig. 14), and a connecting bell crank lever 142 fulcrumed

5 at 143 on standard 144 which is supported by a cross member 145 resting upon supports 146. The bell crank 142 is provided at its opposite end with a slotted opening 147 in which rides pin 148 mounted in one side of one of the push rods 149. The push rod 149 is slidably supported at one end in a slotted guide plate 150 carried by the support 146, the other end of the push rod 149 riding in a slotted guide plate 151 which is a part of the selector C. Each of the push rods 149 is provided with a stop 152 which is designed to contact one of the notches 153 in stop plate 154 located above the push rods and secured to the 10 guide plate 151.

The selector C is a device adapted to transmit 15 movement originating in a keyboard to the several numeral wheels and consequently to the meter set-up mechanism E by progressive movements accomplished through the use of an escapement device which permits the lateral travel 20 of part of the selector unit to place the contacting member successively in alignment with each of the rack bars 52 of the numeral printer D. This selector device is the subject of a co-pending application, but I will describe its connection with 25 the numeral printer D to illustrate the method of setting up the numeral wheels within the printer.

The selector C is composed of a frame portion 155 supporting a bed plate 156 which acts as a tie between the various parts of the frame 155, as 30 a guide plate for the rack bars 56, 57, and 58, as a supporting member for the guide plate 157, and as a support for the pawl 158, the roller bearings 159, and their supporting frame 160; frame 160 acts as a guide plate for the selector carriage 161 35 which rides between and is supported by the bearings 159, operating in the grooved tracks 162 in the carriage 161.

The carriage 161 is actuated by one of the 40 keyboard-operated push rods 149, and moves the carriage 161 longitudinally whereby the selector arm 163 contacts one of the rack bars 52 and moves it in the same longitudinal direction a distance equivalent to the number represented 45 by the particular key depressed on the keyboard A. The selector arm 163 which is secured to the slide member 164, is close to one side of the selector unit, that is, adjacent one of the frames 155 (Fig. 1). This position will be termed the original position of the selector; as the keyboard 50 A is operated, the slide 164, carrying the selector arm 163, is given a step-by-step motion in accordance with the operation of the escapement, the slide traveling in a direction transverse to the direction of movement of the carriage 161, 55 thereby placing the selector arm 163 successively in a position to contact and move each of the rack bars 52 longitudinally in succession.

The means for providing this successive step 60 movement consists of the pawl 158 which operates against a ratchet toothed member 165 located immediately beneath and secured to the slide 164 which is tensioned for escapement travel by a spring (not shown). Upon a lateral movement 65 of the selector carriage 161 (to the left in Fig. 14) the tooth opposite the guide plate 151, which would be held by the pawl 158, moves along the guide plate 151 and frees the pawl 158 from ratchet toothed member 165, the pawl then, by spring tension, moving toward the next tooth in 70 line being limited in its movement to a distance of one tooth by a stop (not shown), thus allowing the tooth previously engaged, upon the return of the carriage 161 to original position, to pass by the pawl; the pawl will then engage the 75

next succeeding tooth as it is brought toward it by slide 164 and will stop it by reason of engagement of the pawl with a stop (not shown) at a position in which the selector arm 163 is aligned with 5 the next succeeding rack bar 52.

This successive step by step movement is shown and described in a co-pending application of George W. Lawrence, filed October 23, 1931, Serial Number 570,622.

- 10 This movement occurs upon the depression of each succeeding key on the keyboard until the selector slide 164 has been operated six times, when it is at the limit of its movement, (in a position opposite to that shown in Fig. 1). The 15 operation of returning the slide to original position will be described in connection with the error mechanism and the releasing action of the pawls 106 for returning the rack bars 52 to original position.
- 20 The next step in the progression of movements from the keyboard A is the actuation of the meter set-up mechanism E. This actuation for the setting up of the mechanical equivalents of numbers within the meter set-up mechanism occurs 25 simultaneously with the actuation of the racks 52 by means of the connecting elements 55 which terminate in the three racks 56, 57, and 58. The meter-actuation mechanism is adapted to handle only monetary values to be printed upon a stamp; 30 in the machine herein disclosed, there are three monetary values, the cents, tens of cents, and dollars, and three corresponding operating parts of the mechanism, namely the racks 56, 57, and 58: the dollars are transferred by the rack 58, 35 the tens of cents by the rack 57, and the cents by the rack 56.

The series of pinions, shafts, and gears 166 (Fig. 3) transmit the keyboard movement to a series of stepped elevators 167 which are moved 40 to a position wherein the particular step which is so positioned becomes the mechanical equivalent of the number punched in on the keyboard A and determines the degree of movement of the meter actuating mechanism (not shown). At 45 the time a printing operation occurs, power is transmitted to the meter-actuating mechanism by means of secondary drive shaft 63 and its connections 170 to shaft 171 whereon a series of cams, (not shown), are so disposed that they 50 will, when operated, successively actuate the elevators 167 and the associated meter actuating mechanism, beginning with the cents and progressing through the tens of cents and dollars; this is done for the purpose of allowing the 55 meters to perform their carry-over operation from one numeral wheel to the other upon any one of the wheels reaching its ultimate amount or a ten. This form of meter is conventional and will be clearly understood by one conversant with the 60 art, but the meters used in this machine have features of peculiar construction, necessary for the work to be done, and are clearly set forth in a co-pending application, filed October 23, 1931, Serial Number 570,621.

65 The meters to which this application will refer include the re-set meter F, wherein there is provided a means of setting the meter for a pre-determined amount of postage in the form of dollars and cents; means for subtracting at each 70 printing operation the monetary value of the stamp printed; means, operable upon the exhaustion of the pre-set amount to lock the machine. The operation of this lock will be more fully described hereinafter.

The other meter included in this machine is the permanent total meter G; this meter is started at zero and adds into the subsequent reading each monetary amount of the stamp printed by the machine as it is printed; it is sealed against access during the life of the machine. This provides a means of obtaining readings at any time of the monetary values which have been printed upon stamps by the machine; from a series of these readings the amounts of 10 postage which have been used by the machine can be calculated.

15 The re-set meter F is re-set by a post-office official for an amount of postage purchased by the consumer. The permanent total meter G is 15 of identical construction with the re-set meter F.

20 As previously set forth, there is one additional element which controls the operations of the machine and, in a way, acts as a governor by requiring that a certain number of key depressions be performed in the keyboard A before a printing operation can be attained. In the form of 25 parcel post machine herein disclosed it is necessary that there be six key-actuations in the keyboard, this control being exercised by the progressive release lock (Fig. 1). Unless the keys are properly punched in on the keyboard A to effect six key-actuations, the progressive release lock M will not release the locking element of the power clutch L, and consequently will prohibit 30 the release of this clutch by the control key 61 (Fig. 1). This progressive release lock mechanism forms the subject of a co-pending application filed October 23, 1931, Serial Number 570,631.

35 A butterfly 172 (Fig. 14) is so disposed in relation to the key bars 140 that, upon the operation of a key in the keyboard its key bar 140 contacts the upper edge of the butterfly 172 and rocks it upon the rock shaft 173 to which it is secured. 40 The rock shaft 173, mounted in supports 174, has secured to one end a lever 175 to which is connected a link 176; link 176, through intervening connections, operates a link 176a connected to the ratchet device 177 of the progressive release 45 lock M (Fig. 1).

At each depression of a key this ratchet device rotates the ratchet wheel 178 one notch, thus rotating the pins 179 until six keys key-actuations have been performed, when one of the pins 179 50 will have contacted and moved the lock bar 180 longitudinally to move the lock 181 and, through the bell crank 182, to throw the latch 183 out of the path of the pin 184 of power clutch L. This removal of the latch 183 allows the power clutch 55 L to be operated by the control key 61 for printing purposes. The restoring mechanism for returning the various elements of the progressive release lock M to original position will be fully described in the description of the mechanism 60 for clearing the machine.

Immediately adjacent the numeral printer D (Figs. 2 and 5) is a rotary printer H through which the paper tapes pass and wherein the stamp section receives an indicia imprint before it is passed into the numeral printer D for the printing of the date and numerals thereon. This rotary printer provides a simple but effective printer bearing an indicia plate for printing the lettering upon a stamp; its standards 185 and 70 186 act as shaft supports and sustain the inking device.

The drum 187 is secured to the shaft 188 which is rotatably mounted in the standards 185 and 186 and is provided on one end with a drive gear 75

wheel 189 and on the other end with a knurled hand wheel 190 for the purpose of manually operating the printer during a threading-up operation.

- 5 The drum 187 is provided on one portion of its periphery with the indicia plate 191, which, in the form of construction illustrated, occupies approximately one-third of the circumference of the drum 187; for the purpose of providing ink 10 for the indicia plate, this drum is hollow and contains an ink reservoir provided with a filling screw cap 192; a fabric cushion 193 along a portion of the circumference of the drum 187 constitutes a self-feeding ink pad.
- 15 The distribution of ink evenly and efficiently upon the surface of the indicia plate 191 is effected by an inking roller 194 spring-tensioned in supports 195 attached to the standards 185 and 186. This ink roller 194, rotating with the 20 drum in a counter-clockwise direction, as viewed in Fig. 5, contacts the ink pad 193 prior to contacting the indicia plate 191 and thereby receives a fresh supply of ink which it distributes upon the type face of the indicia plate 191, there- 25 by furnishing the indicia plate 191 with a fresh supply of ink immediately before the indicia plate reaches the printing point directly below the center of the shaft 188, at which point the indicia plate 191 contacts a platen roller 196 and ex- 30 ercises a proper printing pressure upon the paper tapes lying between these members.

It is required, in the cycle of operation of the entire parcel post machine, that the stamp tape forwarding means operate only during one-third 35 of the single complete revolution made by the drive shaft 62 during a complete printing operation of the machine. An intermittent clutch is accordingly provided to start and stop the forwarding means at predetermined points in the 40 cycle of operation.

The clutch consists of a continuously rotating drive element 197 secured to the drive shaft 62, and being the drive element of the clutch; for 45 disengaging the clutch for two-thirds of the rotation of the drive shaft 62, the drive element 197 rides on a guide plate 198 (Fig. 5). The plate 198 has an open portion through which, for one-third of the revolution of the drive shaft 62, it projects into driving contact with the driven 50 gear 199, which, through a series of gears, drives the platen shaft 200; the cam 128 on shaft 200 contacts the cam roller 127 attached to the ribbon feed mechanism drive arm 125. This set of gearing also actuates the feed rollers 201 and 55 202 which forward the paper tapes through the machine within the guide plate 119.

In threading up the machine the rotary printer 187 and the rolls 201 and 202 must be rotated. In this operation a conventional pin 60 clutch 204 is disengaged by lever 208 to allow the rotary printer 187, the platen 196, and the feed rolls 201 and 202 to be operated by the hand wheel 190 independently of any other part of the machine. This threading-up operation feeds 65 the paper tapes through the guide plate 119 and, with the knife 131 raised, one paper tape is threaded into the moistener guide 205; the knife is then dropped, the superfluous section of paper tape being cut off and discarded, leaving a section 70 of the paper tape, lying between the rotary printer and extending through the guide plate 119 up to the knife 131.

This section of paper tape, by means of the threading-up operation, has had two prints of the indicia plate 191 made upon it, the length be-

ing sufficient for two stamps; one stamp form lies in the guide plate 119 preparatory to receiving a print from the numeral printer which will make a finished stamp; an additional blank stamp form lies in the space between the rotary printer and the numeral printer ready to be advanced when the next printing operation takes place; the interval allows time for the ink used on the indicia plate 191 to dry, it being preferred that the ink used for the lettering printed upon a stamp have 10 more body than the ink used for numeral printing, which penetrates the paper and dries more rapidly.

The duplicate tape threaded through with the stamp tape is separated below the knife V and 15 is threaded onto a rewind element, not shown, immediately below the moistening element. The moistening element T in (Fig. 2) comprises the guide 205, a tank 206 provided with a moistening roller 207 for carrying the moistening fluid from 20 the tank on to the gummed surface of the stamp, and a pressure and driving roller 208. These two rollers are manually operable by means of the handle 209. Through the gear train 210, also actuated by handle 209, the moistened stamp 25 is forwarded to the discharge spout 211, where it is received by the operator. This moistener forms the subject of a co-pending application, filed October 23, 1931, Serial Number 570,626.

The drive shaft 62 carries a non-reverse element (Fig. 2) consisting of a ratchet wheel 212 provided with a pawl 213 secured to the clutch supporting frame 214, this means positively prevents the operation of any part of the machine in a reverse direction and, in conjunction with 35 the meter control lock mechanism hereinafter to be described, complies with the requirements of the Post Office Department for a machine from which a stamp cannot be surreptitiously obtained.

The meter control locking mechanism for locking 40 machine upon the exhaustion of a pre-set amount of postage within the re-set meter is the subject of a co-pending application, filed October 23, 1931, Serial Number 570,619; it will be described only to the extent necessary detail to clarify its relation to the numeral printer D.

The re-set meter F (Fig. 1), has six numeral wheels, the meter wheel 215, at the left of the train of meter wheels illustrated having on one 50 side a boss 216 adapted to contact a trip 217; when thus released trip 217 moves laterally to allow the drive bar 218 to be lowered into the path of a cam 219 secured to the rock shaft 220; a rock arm 221, also secured to shaft 220, (Fig. 2) 55 has a cam roller 222 riding upon a cam 223 secured to the secondary drive shaft 63.

The rock shaft 220 also operates a set of levers 224 which constitute a power return for the meter actuating mechanism. This operation, occurring 60 at the completion of a printing operation allows the locking operation of the machine, on exhaustion of the re-set meter, to take place after a stamp has been completely printed and discharged from the machine when operated by the cam 65 219, the drive bar 218, through its connections 225 (Fig. 1), actuates a switch element K (Fig. 2) to break the motor circuit. Another element actuated by this operation is the drive shaft lock 226 which comprises a pawl (not shown) which is set against a toothed element 228 secured to the drive shaft 62, thereby locking the machine positively against rotation in a forward direction and, in conjunction with the non-reverse elements 70 75 75

212 and 213, locking the machine against rotation in either direction.

For the purpose of re-setting the re-set meter F and releasing the locking elements, I have provided a key lock element 229 which, among other connections, has a trip re-setting member 230 which contacts the trip 217 and the drive bar 218, returning them to their original position. The key lock element 229 prevents any access to or tampering with the re-setting member, the key for this lock being intended to be in possession of the postoffice officials.

The clearing mechanism may be operated for clearing the machine of any set-up contained therein, either manually or at the completion of a printing operation. The machine, through its drive elements at the completion of a printing operation, automatically clears the machine preparing it for the next set-up mechanism and printing operation; or the clearing operation may be manually effected by the operator by means of the error key 231 in keyboard A.

Depression of the error key 231 depresses the key bar 140^a (Fig. 14). The butterfly 172 has a cut-out portion providing for the operation of the key 140^a therein without contacting the butterfly 172. The key bar 140^a, when depressed, contacts a rocking lever 232 secured to a shaft 233 supported by standards 234. A lever 235, secured to shaft 233 is connected to a link 236 (Fig. 14) which is connected to a rock arm 237 secured to the rock shaft 238 (Fig. 1).

This rock shaft 238 connects with a secondary rock shaft 239 by means of a set of levers 240 (Fig. 2) this secondary shaft 239 has secured to it a lever 241 which is operated by cam 242 at the completion of a printing operation. A lever 243 on the secondary shaft 239 contacts a slidable shaft 244 and moves it axially for the purpose of releasing the pawls 106 which retain the rack bars 52 in a set-up position. The shaft 244 is tensioned by spring 245 toward the lever 243, in which position the pawls 106 properly engage the teeth 105 in the rack bars 52; when the clearing operation takes place, the axial movement of the shaft 244 moves the pawls 106 out of engagement with the teeth 105 and, as the rack bars 52 are spring-tensioned, they tend to return to their normal position; a more positive return of the rack bars 52 to original position is effected by bar 115 (Fig. 8), as hereinbefore described.

This return of the rack bars 52 to original position returns the elevators 167 and the meter set-up mechanism E to original position preparatory to a new set-up being made by means of the keyboard A.

As previously described, the progressive release lock M is re-set to original position by means of the clearing mechanism whenever it is operated; to that end a lever 246 is secured to the rock shaft 238 and has on one end a bifurcated section to which is secured the rack bar 247, the rack section of which meshes with a pinion 248 of the progressive release lock mechanism, by this means the rotative elements of the progressive release lock mechanism are returned to normal position both upon completion of a printing operation when the error rock shaft 238 is operated upon completion of a printing operation and when the error rock shaft 238 is manually operated from the keyboard by the error key 231.

Thus, by the operation of clearing the machine the progressive release lock is returned to original position and the power clutch L is positively locked against operation until the required num-

ber of key-actuations have been effected upon the keyboard A.

The power clutch L consists of a novel form of pin clutch mechanism, which is positively disengaged at a predetermined point in the cycle of operation, and which is disclosed in a co-pending application filed October 23, 1931, Serial Number 570,636. I will not describe this clutch in detail as, beyond its connecting the source of power with the drive shaft 62, it has no bearing upon 10 the numeral printer D.

For the purpose of indicating to the operator whether he has made a correct set-up in the machine of the monetary value required for printing on a stamp, I have provided a set of indicator wheels 249 which are directly connected to a portion of the meter set-up mechanism E and are set up and returned to original position with the elements of this unit; these wheels give a visual indication of the set-up.

Should the paper tape break or become exhausted or by any other means fail to be supplied to the printers, the motor circuit will be broken and a signal displayed by means of the electric trips 250 (Fig. 4) of the paper roll unit N. The trips have a connection extending to the solenoid 251 in the solenoid switch unit O, so that, upon the closing of the contact 250 the solenoid 251 is operated and by means of the connected switches the motor circuit is opened and a signal circuit 30 closed. This mechanism, which is re-set manually by the operator upon remedying the trouble indicated, is the subject of a co-pending application filed October 23, 1931, Serial Number 570,630.

For the purpose of leaving the machine in a condition whereby it cannot be operated except by an authorized person, I have provided a key lock (not shown) which has a connecting arm 253 extending (as shown in Fig. 4) to the main switch Q and which, when rotated in withdrawing the key from the lock, opens the switch Q and disconnects the current from the entire machine; the current is supplied by the main line 254 and the plug connection 255.

For the purpose of preventing the machine 45 from being operated during the threading-up operation, the portions of the machine wherein the threading-up operation takes place are securely partitioned off from the balance of the machine; access to this part of the machine is gained 50 through a door, (not shown), in the side of the machine at approximately 256 on Fig. 4; an electric switch 257 of conventional design breaks the motor circuit when the door is opened and automatically closes the circuit when the door is 55 closed.

During the printing cycle of the parcel post machine the movements executed by the numeral printer are so timed that the interval of time allotted to the numeral printer allows sufficient 60 time for the other operations required to complete a printing cycle.

The cycle of operation of the machine is instituted by the depression of the control key 61 by the operator of the machine when the printing operation is desired. This control key 61 connects the clutch L, thereby transmitting power from the electric motor R and its connections S, to the drive shaft 62, from which the power is distributed to the various operating elements of 70 the machine. The first connection from which power is taken off the drive shaft 62 is the secondary drive shaft 63, (Fig. 2), which conveys power to the numeral printer D and the meter-actuating mechanism E.

The next distribution of power is to the rotary printer H where there is a further distribution through the cam 128 to the ribbon feed U (Fig. 10) to the paper feed rollers 201 and 202 (Fig. 5). 5 At approximately the completion of the printing operation, there is an additional distribution of power from the drive shaft 62 through the cam 242 (Fig. 2) to the clearing mechanism of the machine; at approximately the same point in the 10 cycle of operation there is a distribution of power to the return elements of the meter-actuating mechanism E from the secondary drive shaft 63 by means of the cam 223 (Fig. 2); as a final distribution of power for actuating purposes the 15 power clutch L is disconnected by means of a cam 258 (Fig. 1) which actuates one of the elements of the clutch to cause its disengagement at a predetermined point in its revolution.

The first operation that takes place in the cycle 20 of operation wherein the drive shaft 62 makes a single revolution is the actuation of the inking device for inking the type faces in the numeral printer D; the roller 101, actuated by means of cam 89 (Fig. 11) on the driven shaft 66, is caused 25 to pass over the ink pad 102 and across the type faces and is then returned to its original position back of the ink pad 102. This movement is rapid and is timed to occur previous to the downward movement of the numeral printer D. 30 The next operation is the actual printing movement of the numeral printer D; the hammer 45 is caused to descend by means of the cam 67 when the cam roller 70 reaches that portion of the cam groove 69 wherein it may move freely in one direction; the pin 73 on the periphery of the cam 67, having been rotated to the point where it contacts the trip 75, removes the latch 74 from contact with the pin 73, thus releasing the lever 71 which, being heavily tensioned by spring 72, 35 rocks the shaft 48 and consequently the arms 49 which support and actuate the hammer 45 (Figs. 6, 7 and 8).

The hammer 45, in its descent, engages the particular type member of each numeral wheel 45 presented thereto and locks the wheels in position before it reaches the point at which it disengages the pinions 54 from the rack teeth 53. The hammer-operated printer, at the end of its descent, contacts the paper tapes with the ink 50 ribbon lying between them, thus making a print on both the original stamp itself and the duplicate paper tape. The return of the numeral printer to its original position is effected by the further rotation of cam 68, the roller 70 being 55 acted upon by the sides of the cam groove 69 to rock the lever 71 and, consequently, the shaft 48, thereby returning the various parts to their original positions.

The stamp having been printed, it is forwarded 60 out of the path of the numeral printer a stamp length distance into the adjacent discharge and moistening element; a stamp form is also printed by means of the indicia plate 191 on the rotary printer H; for the latter purpose, I have provided 65 the rotary printer clutch, (Figs. 2 and 5), which is timed to engage immediately that the return movement of the numeral printer reaches a point at which the type faces have been removed a sufficient distance from the paper tapes to prevent 70 contact therewith upon a forwarding movement of the tapes.

In the actuation of the rotary printer H and its gearing the paper tape is forwarded a stamp length to bring the stamp form just printed into 75 the proper position beneath the numeral printer;

co-ordinately therewith the paper tape is forwarded and, while passing beneath the printing drum 107, is contacted thereby to receive a print of the indicia plate 191. This operation of the rotary printer rotates shaft 200, (Fig. 5), to which is secured (Fig. 2), the cam 128 which actuates the ribbon feed mechanism U and which, at this point in the cycle of operation moves the ink ribbon a sufficient distance to bring a fresh surface into the path of the numeral printer D. 10

During this interval of time the actuation of the serial numbering device occurs; the cam 79 having rotated to a position where it allows the lever 81 to rock, thus advancing the serial numbering device one number and preparing it for the 15 next printing operation. Another operation that occurs during the printing operation of the numeral printer D is the operation of the meter-actuating mechanism E; the secondary drive shaft 63, through its connected gearing, rotates the 20 cams which lift the elevators in the meter-actuated mechanism and thereby transfer to both the re-set and the permanent total meters the mechanical equivalents previously set up; this operation is completed by the time the numeral printer D has returned to original position, with the hammer 45 disengaged from the type members; at this point the clearing operation is commenced. 25

The operation of clearing the machine of the 30 set-ups made previous to the printing operation is instituted by the rotation of the cam 242 on drive shaft 62 actuating the contacting lever 241 which is secured to the error rock shafts 238 and 239. The actuation of these two shafts institutes movements in several operating members, one of 35 which is the slide shaft 244, to which are secured pawls 106 and by which the pawls are drawn out of engagement with the teeth 105 in the rack bars 52, permitting the return of the rack bars to original position. 40

Another movement occurring as part of the clearing action is the return of the progressive release lock M to original functioning position wherein the connected elements act to lock the power clutch L against being connected by the 45 control key 61 until a new set-up has been made in the keyboard A. Another operation that is instituted by the clearing operation is the return of the selector slide 164 with its attendant selector arm 163 to the original position (Fig. 1), 50 which is accomplished by means of the selector return arm 259 which is connected to the rock shaft. 55

An additional operation occurs immediately following this clearing action, and is instituted at a 55 point in the cycle of operation where the pawls 106 clear the teeth 105 in the rack bars 52; the cam 116 actuates the contacting levers 110, 114, and 113 to rock the rod 115 through the path of the connecting elements 55 attached to the rack 60 bars 52, and thereby returns the rack bars 52 by power action to their original position, if they have failed to return automatically under the tension of the springs 107.

Another operation which occurs at approximately 65 the completion of the printing operation of the machine, and after the clearing operation has taken place, is a power return movement for the meter-actuating mechanism E which is instituted by the cam 223 upon secondary drive shaft 70 63; this cam contacts cam roller 222, thereby rocking the shaft 220 to which are secured levers 224 which contact the elements of the meter-actuating mechanism. The rocking of the shaft 220 has an additional function in the actuation 75

of the meter control lock mechanism by the rocking of a cam 219 secured to this shaft in the event that the meter control lock mechanism has been tripped, as upon the exhaustion of a pre-set amount in the re-set meter; the cam 219 therefore actuates the locking mechanism for the machine, which is timed to act at the exact completion of the cycle of printing operation.

Assuming that the printed stamp has been forwarded into the moistener and discharge element T, the final operation of the machine occurs with the releasing of the knife V for the purpose of severing the printed stamp from the continuous paper tape fed to and through the machine. This operation is instituted by the cam 136 secured to the shaft 66, the cam roller 137 dropping into the dwell 139 and the lever 134 operating the knife 131 (Fig. 6). The knife remains in the down position at the completion of a printing operation and is raised to clear the path of the stamp during the next succeeding printing operation. For the purpose of threading the paper tape through the machine, this knife is raised manually by the lift 132.

While the form of mechanism here shown and described is adapted to fulfill the objects primarily stated, it is to be understood that it is not intended to confine the invention to the one form of embodiment herein disclosed, for it is susceptible of embodiment in various forms, all coming within the scope of the claims which follow.

I claim:

1. In a device of the character disclosed, adjustable numeral printing wheels normally maintained in a zero reading position, a keyboard including keys; operating mechanism adapted to connect one of the keys in said keyboard with every numeral printing wheel in a successive contact relation for the purpose of setting up numerical combinations in said numeral wheels, ratchet elements adapted to engage said operating mechanism to maintain said numeral wheels in their set-up relationship, and clearing mechanism adapted to be operated by a key in said keyboard to release said ratchet elements to permit return of said numeral wheels to zero reading position.

2. In a device of the character disclosed, numeral printing wheels adapted to perform a printing operation and normally maintained in a zero reading position, a keyboard including keys; operating mechanism adapted to connect one of the keys in said keyboard with every numeral wheel in a successive contact relation to set up numerical combinations in said numeral wheels; ratchet elements adapted to engage said operating mechanism to maintain said numeral wheels in their set-up relationship; and re-setting mechanism adapted to automatically operate to release said ratchet elements to permit the return of said numeral wheels to their zero position upon completion of a printing operation.

3. In a device of the character disclosed, adjustable numeral printing wheels normally maintained in a zero reading position; a keyboard including keys; a selector; said selector being operated from an initial position by a key and thereafter successively positioned to operate said numeral wheels and set-up therein numerical combinations; ratchet elements adapted to maintain said numeral wheels in a selected set-up combination; and keyboard operated clearing mechanism to release said ratchet elements, the said numeral wheels thereby being free to return to zero reading position.

4. In a device of the character disclosed, ad-

justable numeral printing wheels normally maintained in a zero reading position; a keyboard including keys; a selector adapted to be operated from an initial position by a key and thereafter successively positioned to operate said numeral wheels and set up therein numerical combinations; ratchet elements adapted to maintain said numeral wheels in a selected set-up combination, and keyboard operated clearing mechanism to release said ratchet elements, the said numeral wheels thereby being free to return to zero reading position; said clearing mechanism including means to return said selector to an initial position preparatory to the next set-up operation.

5. In a device of the character disclosed, adjustable numeral printing wheels adapted to perform a printing operation and normally maintained in a zero reading position; a keyboard including keys; a selector adapted to be operated from an initial position by a key and thereafter successively positioned to operate said numeral wheels and set up therein numerical combinations; ratchet elements adapted to maintain said numeral wheels in a selected set-up combination, and re-setting mechanism adapted to automatically operate to release said ratchet elements to permit the return of said numeral wheels to their zero reading position upon completion of a printing operation.

6. In a device of the character disclosed, adjustable numeral printing wheels adapted to perform a printing operation and normally maintained in a zero reading position; a keyboard including keys; a selector adapted to be operated from an initial position by a key successively positioned to operate said numeral wheels and set up therein numerical combinations; ratchet elements adapted to maintain said numeral wheels in a selected set-up combination; and re-setting mechanism adapted to automatically operate to release said ratchet elements to permit the return of said numeral wheels to their zero reading position upon completion of a printing operation; said re-setting mechanism including means to return said selector to an initial position preparatory to the next set-up operation.

7. A device of the character disclosed; a numeral printer including a series of adjustable numeral printing wheels and a dater; a keyboard; operating mechanism adapted to be operated by a key in said keyboard to set up said numeral wheels to numerical combinations; said dater being removable and normally positioned in said printer adjacent to and in alignment with said numeral wheels; a motor adapted to operate said printer for a printing operation; an electric circuit for said motor; and a switch in said circuit adapted to be closed when said dater is positioned adjacent to and in alignment with the numeral wheels.

8. In a device of the character disclosed, a numeral printer including a series of adjustable numeral printing wheels and a dater; a keyboard; operating mechanism adapted to be operated by a key in said keyboard to set up said numeral wheels to numerical combinations; said dater being removable and normally positioned in said printer adjacent to and in alignment with said numeral wheels; a motor adapted to operate said printer for a printing operation; an electric circuit for said motor; and a switch in said circuit adapted to be opened when said dater is out of alignment with the numeral wheels of said printer.

9. In a device of the character disclosed, a

- numeral printer including: a series of adjustable numeral printing wheels, an automatic numbering device, and a dater; a keyboard; operating mechanism adapted to be operated by a key in 5 said keyboard to set up said numeral wheels to numerical combinations; said dater being removable and normally positioned in said printer adjacent to and in alignment with said numeral wheels; said automatic numbering device comprising printing numeral wheels adjacent to and in alignment with said adjustable numeral wheels and said dater; said numbering device being adapted to be actuated to increase one unit for each printing operation of the printer.
10. In a device of the character disclosed, a printer having rotatable numeral printing wheels; and a printing hammer formed to engage and lock said printing wheels against rotation during a printing operation.
15. 11. In a device of the character disclosed, a printer having rotatable numeral printing wheels; and a printing hammer formed to engage and lock said printing wheels against rotation, and simultaneously actuate the same to perform 20 a printing operation.
20. 12. In a device of the character disclosed, a reciprocating printing frame; numeral printing wheels rotatably mounted in said frame; a date printing device removably mounted in said frame 25 in alignment with said numeral wheels; a serial number printing device mounted in said frame in printing alignment with said numeral wheels and said date device; and means to operate said frame and elements carried thereby to co-ordinately perform a printing operation.
25. 13. In a device of the character described, adjustable numeral printing wheels normally maintained in a zero reading position, a keyboard including keys, operating mechanism for connecting each of said keys with any one of said 30 numeral printing wheels for setting up numerical combinations in said numeral wheels, locking means for engaging said operating mechanism to maintain said numeral wheels in set-up relationship, and key-actuated means for releasing said locking means to permit return of said numeral 35 wheels to zero reading position.
30. 14. In a machine of the character described, a numeral printer comprising adjustable printing wheels and a removable dater, a keyboard, 40 key actuated operating mechanism for setting up numerical combinations on said numeral wheels, means for actuating said printer for a printing operation, and means for preventing operation 45 of said printer actuating means when said dater is displaced from its normal position in said numeral printer.
45. 15. In a device of the character described, adjustable printing wheels adapted to perform a printing operation, a keyboard having keys, a key-actuated selector for operating said wheels 50 to set up character combinations thereon, printing means for locking said wheels in a selected set-up combination and for actuating said wheels 55 while in locked condition to perform a printing operation, and re-setting mechanism for releasing said wheels to permit the return of said wheels to initial position.
55. 16. In a device of the character described, adjustable printing wheels adapted to perform a printing operation, a key-actuated selector for successively operating said wheels to set up character combinations thereon, printing means for maintaining said wheels in a selected set-up combination and for actuating said wheels to per-
60. form a printing operation, and re-setting means for automatically releasing said wheels to permit the return of said wheels to initial position upon completion of a printing operation.
65. 17. In a device of the character described, a printer having movable printing members, a key-actuated means for setting said printing members, and an operating member for engaging and locking said printing members in set-up relation and simultaneously actuating said printing members to perform a printing operation.
70. 18. In a machine of the character described, a numeral printer comprising adjustable printing wheels, a keyboard having keys, operating mechanism for connecting each of said keys with any one of said printing wheels for setting up numerical combinations in said printing wheels, and an operating member for engaging and locking said printing wheels against rotation and for actuating said printing wheels to perform a printing operation.
75. 19. In a machine of the character described, a numeral printer comprising adjustable printing wheels, a keyboard having keys, operating mechanism for selectively connecting each of said keys with said printing wheels for setting up numerical combinations in said printing wheels, an operating member for engaging and locking said printing wheels against rotation and for actuating said printing wheels to perform a printing operation, and re-setting means for releasing said operating member from locking engagement with said printing wheels to permit the return of said wheels to initial position upon completion of a printing operation.
80. 20. In a device of the character described, a printer having rotatable printing wheels, and means for locking said printing wheels against rotation and for actuating said printing wheels to perform a printing operation.
85. 21. In a device of the character described, a printer having rotatable printing wheels, and an operating member for engaging and locking said printing wheels against rotation and simultaneously actuating said printing wheels to perform a printing operation.
90. 22. In a device of the character described, a printer having rotatable printing wheels, having teeth thereon, and a printing hammer having a recess therein adapted to receive a tooth of one of said wheels for locking said wheel against rotation and simultaneously actuating said printing wheel to perform a printing operation.
95. 23. In a device of the character described, a printer having rotatable printing wheels having type teeth thereon, a printing member, a locking device carried by said printing member having a recess therein adapted to receive a type tooth of each of said wheels to lock said wheels against rotation, and means for moving said printing member and its locking device for locking said wheels against rotation and for moving said locked wheels to perform a printing operation.
100. 24. In a device of the character described, a printer comprising a frame, a support slidably positioned on said frame, printing wheels rotatably mounted on said support and having projecting type thereon, and a printing member slidably on said frame and having a recessed face adapted to receive a type of each of said wheels to lock said wheels against rotation, and means for moving said printing member into engagement with said wheels for locking said wheels.

wheels against rotation and for moving said wheels to perform a printing operation.

25. In a device of the character described, a printer comprising a frame, a support slidably positioned on said frame, printing wheels rotatably mounted on said support and having projecting type thereon, a printing member slideable on said frame and having a recess in its face adapted to receive a type of each of said wheels to lock said wheels against rotation, means for

sliding said printing member on said frame into engagement with said wheels for locking said wheels against rotation and for sliding said support and the wheels mounted thereon into position to perform a printing operation, and spring means for releasing said printing member from locking engagement with said wheels to permit the return of said wheels to initial position upon completion of a printing operation. 5

WILLIAM J. PEARSON. 10
